CLAIM

The ornamental design for a flush mount LED bolt head, as shown and described.

DESCRIPTION

FIG. 1 is a perspective view of a flush mount LED bolt head showing our new design;

FIG. 2 is a front view thereof;

FIG. 3 is a right side view thereof, the left side view being a mirror thereof; and,

FIG. 4 is a top view thereof, the bottom view being a mirror image thereof.

The broken lines in the drawings represent environmental structure and it forms no part of the claimed design.
